his Attorney.

UNITED STATES PATENT OFFICE.

HARRY DAILEY, OF OKLAHOMA, OKLAHOMA.

RAIL-JOINT.

949,415.

Specification of Letters Patent. Patented Feb. 15, 1910.

Application filed October 28, 1909. Serial No. 525,037.

To all whom it may concern:

Be it known that I, HARRY DAILEY, a citizen of the United States, residing at Oklahoma city, county of Oklahoma, and State 5 of Oklahoma, have invented certain new and useful Improvements in Rail-Joints, of which the following is a specification.

My invention relates to improvements in rail-joints, the object of the invention being 10 the provision of a rail-joint which shall be inexpensive of production, efficient and reliable in service, and strong and durable.

A further object of my invention is to provide a self contained rail-joint so constructed 15 as to obviate the necessity of using the ordinary fish-plates and connecting bolts.

Other objects will appear hereinafter.

With these objects in view my invention consists in the novel construction and arrangement of parts which will be herein-after fully described and more particularly 20 pointed out in the appended claims.

My invention will be best understood by reference to the accompanying drawings 25 forming a part of this specification, and in which,

Figure 1 is a perspective view showing the end of one rail of the joint, Fig. 2 is a perspective view showing the end of the 30 other rail of the joint, Fig. 3 is a perspective view showing the near ends in position prior to locking the joint, and Fig. 4 is a perspective view showing the completed joint.

Referring now to the drawings, 1 designates one rail and 2 the other. The cross 35 sectional area of the rails are uniform and unchanged before the formation of the joint, no enlargement in the rails being required.

The ends of the rails are formed into heads 40 and head receiving sockets as will be described hereinafter so that when one rail is properly positioned it will fall into engagement with the other by gravity and be securely locked thereto.

The rail 1 is provided with a reduced portion 3 in the tread thereof, a head 4 being formed on said reduced portion, and a socket 5 is formed in the tread of the other 45 rail to receive the portion 3 and head 4 as shown in the several figures. The rail 2 is provided with a reduced portion 6 in the tread thereof, and a head 7 similar to the head 4 is formed thereon. The aperture or 50 socket 8 is formed to receive the head 7 as shown in Fig. 4. The reduced portions 3

and 6 have inclined surfaces in order to provide the proper clearance between each other, these surfaces being contiguous when the joint is completed. The web 9 of the 60 rail 2 is recessed at 10 and a tongue 11 is formed on the web 12 of the rail 1 to engage this recessed portion, the height of said tongue being equal to the height of the web of the rail. Sockets 13 are formed in each 65 flange of the rail 2 and reduced portions 14 having heads 15 in the rail 1 are adapted to engage these sockets. Lateral longitudinally extending fingers 16 are formed in the tread of the rail 1 and recessed portions 17 of the 70 rail 2 are formed to receive said fingers.

While I have shown what I deem to be the preferable form of my invention I do not wish to be limited thereto as there might be various changes made in the details of construction and arrangement of parts described without departing from my invention, and hence I desire to avail myself of such changes and alterations as fairly fall within the spirit and scope of the appended 80 claims.

Having described my invention what I claim as new and desire to secure by Letters Patent is:—

1. In a rail joint, two rails, each of which 85 has a socket formed in the tread thereof adjacent their contiguous ends, a reduced portion in the tread of each rail terminating in a head, the said head on one rail being adapted to engage the said socket of the 90 other, a socket formed in the flange of one rail, and a reduced extension and head formed in the flange of the other rail adapted to engage said last named socket, substantially as described. 95

2. In a rail joint, two rails, each of which has a socket formed in the tread thereof adjacent their contiguous ends, a reduced portion in the tread of each rail terminating in a head, the said head on one rail being adapted to engage the said socket of the other, a socket formed in each flange of one rail, a reduced extension and head in each flange of the other rail adapted to engage said last named sockets, a recessed portion in the web 105 of one rail, and a tongue in the web of the other rail adapted to engage said recessed portion, substantially as described.

3. In a rail joint, two rails, each of which has a socket formed in the tread thereof adjacent their contiguous ends, a reduced portion in the tread of each rail terminating in 110

a head, the said head on one rail being adapted to engage the said socket of the other, a socket formed in each flange of one rail, a reduced extension and head formed in each 5 flange of the other rail adapted to engage said last named sockets, a recessed portion in the web of one rail, a tongue in the web of the other rail adapted to engage said recessed portion, lateral longitudinally extending fingers formed in the tread of one rail, 10 and recessed portions adapted to receive the latter formed in the other rail, substantially as described.

4. In a rail joint, two rails, each of which 15 has a socket formed in the tread thereof adjacent their contiguous ends, a reduced portion in the tread of each rail terminating in a head, the said head on one rail being adapted to engage the said socket of the other, a 20 socket formed in each flange of one rail, a reduced extension and head formed in each flange of the other rail adapted to engage said last named sockets, a recessed portion in the web of one rail, a tongue in the web of 25 the other rail adapted to engage said recessed portion, lateral longitudinally extending fingers formed in the tread of one rail and recessed portions adapted to receive the latter formed in the other rail, said heads 30 being substantially semi-circular in form, substantially as described.

5. In a rail joint, two rails, each of which has a socket formed in the tread thereof adjacent their contiguous ends, a reduced portion 35 in the tread of each rail terminating in a head, the said head on one rail being adapted to engage the said socket of the other rail, a socket formed in each flange of one rail, a

reduced extension and head formed in each flange of the other rail adapted to engage 40 said last named sockets, a recessed portion in the web of one rail, a tongue in the web of the other rail adapted to engage said recessed portion, lateral longitudinally extending fingers formed in the tread of one rail, 45 and recessed portions adapted to receive the latter formed in the other rail, said reduced portions having inclined surfaces, substantially as described.

6. In a rail joint, two rails, each of which 50 has a socket formed in the tread thereof adjacent their contiguous ends, a reduced portion in the tread of each rail terminating in a head, the said head on one rail being adapted to engage the said socket of the 55 other rail, a socket formed in each flange of one rail, a reduced extension and head formed in each flange of the other rail adapted to engage said last named sockets, a recessed portion in the web of one rail, a tongue in the web of the other rail adapted to engage said recessed portion, lateral longitudinally extending fingers formed in the tread of one rail, and recessed portions adapted 60 to receive the latter formed in the other rail, said reduced portions having inclined surfaces, the height of said tongue being substantially equal to the height of the rail web, substantially as described.

In testimony whereof I have signed my 70 name to this specification in the presence of two subscribing witnesses.

HARRY DAILEY.
